UNITED STATES PATENT OFFICE.

HUBERT LESLIE STRINGER, OF ROCKBEARE HILL, NEAR EXETER, ENGLAND.

APPARATUS FOR CONVERTING VIBRATORY MOTION INTO ROTARY MOTION.

Application filed November 14, 1922, Serial No. 600,939, and in Great Britain December 8, 1921.

This invention relates to apparatus for converting vibratory motion into rotary motion and is particularly useful for the conversion of small and irregular vibrations such as are produced on or by vehicles.

Many attempts have been made to utilize the vibrations of vehicles, generally for the purpose of actuating moving advertisements, but none of the means hitherto employed for converting the vibratory motion into rotary motion has proved entirely satisfactory in practice. This is probably because the small and irregular vibrations require a more delicate form of ratchet than is generally employed.

According to this invention I employ the usual arrangement of a weight mounted on a spring in such a way that it will readily vibrate backwards and forwards in one line, 20 I place the pulley which is to be rotated in this line, and a fix a thread to the weight, pass it over the pulley, and attach it to a light spring. As the weight vibrates it alternately applies and removes the tension on 25 one end of the thread while the spring produces a small but continuous tension on the other end. Consequently as the weight approaches the pulley there is a tension on one end only and the thread slides easily over 30 the pulley, but as the weight recedes from the pulley there is a tension on both ends and the thread grips the pulley and turns it.

Two or more weights with their threads passing over the same pulley or over separate pulleys on the same shaft may be employed, and such weights are preferably arranged so that their lines of vibration are equally spaced around the pulley. Whenever the number of weights is small, and 40 particularly when only one weight is employed, it is desirable to provide a device for preventing the rotation of the pulley in the wrong direction, as otherwise the thread might have sufficient friction to turn a light 45 pulley instead of sliding over it on the approach of the weight towards the pulley. This device is conveniently a thread passing over the pulley and fixed at one end to the rigid frame and at the other to a light 50 spring, so that the pulley turns easily in the direction which tightens the spring and removes the tension at the other end of the thread, but is prevented from turning in the other direction because the thread having a 55 tension at each end grips the pulley.

In the drawings illustrating my invention,

Fig. 1 is a diagrammatic representation of one form of my invention and Fig. 2 is a side elevation of the rotatable element.

In the figure *a* is the weight mounted on 60 the flat spring *b*, the other end of which is fixed by the foot *c* in the box *d*. The thread *e* is attached at one end to the weight *a*, passes once around the pulley *f*, and is attached at the other end to the flat spring *g*. 65 The flat spring *g* keeps the thread *e* in tension and is fixed by the foot *h* in the box *d*. The thread *i* is attached at one end to the box *d*, passes once around the pulley *f*, and is attached at the other end to the flat spring *j*, 70 which is fixed by the foot *k* in the box *d*. The threads *e* and *i* preferably lie in separate grooves on the pulley *f*, and the thread *e* may also lie in a groove on the weight *a*.

The pulley *f* will then have a rotary motion 75 in the clockwise direction when the whole box is subjected to vibration, as for example when mounted in a vehicle, or even in a shop window past which heavy traffic is passing.

The word thread is not intended to limit the material, but only to indicate the preferred size and shape of the flexible cord employed, and the drawing is only intended to show the preferred form of the device. For 80 example the thread *i*, instead of being attached to the box, may be attached to another weight mounted on a spring and vibrating in a line at right angles to that of the weight *a*, and either or both of the 85 threads may be in contact with the pulley over any other angle, instead of over 360° as shown.

What I claim as my invention and desire to secure by Letters Patent is:—

1. An apparatus for converting vibratory motion into rotary motion, comprising a support, spring members secured to said support and extending longitudinally therefrom in parallel relation, a weighted vibratory member secured to the free end of one spring member, a circular member rotatably mounted between said spring members, and a thread surrounding said circular member and having its ends extending oppositely in 100 a line tangential to the periphery of said circular member and secured respectively to said weighted member and to the free end of the other spring member.

2. An apparatus as set forth in claim 1, 110 and a second thread surrounding said circular member and secured at one end to said

support and elastically tensioned at its other end.

3. An apparatus for converting vibratory motion into rotary motion, comprising a support, a member rotatably mounted in said support, a weighted member spring-mounted in said support, a thread engaging said rotatable member and attached at one end

to said weighted member and tensioned at its other end, and a second thread engaging 10 said rotatable member and anchored at one end to said support and elastically tensioned at its other end.

In witness whereof I affix my signature.

HUBERT LESLIE STRINGER.
